M. HENRY

GREASE CUP

Filed Sept. 15, 1926

M. Henry,
INVENTOR
BY Victor J. Evans

WITNESSES:

ATTORNEY

P. J. Henry.

UNITED STATES PATENT OFFICE.

MICHAEL HENRY, OF TERRE HAUTE, INDIANA.

GREASE CUP.

Application filed September 15, 1926. Serial No. 135,655.

This invention relates to improvements in grease cups, the general object of the invention being to provide a removable cap for the cup which carries a spring plunger for automatically forcing the grease from the cup into the bearing, with spring means for holding the locking means of the cap in operative position.

Another object of the invention is to so place the spring that it will remain on the cup where it will be compressed by the cap as the cap is placed on the cup, with a socket in the cap for receiving a part of the spring so that the spring is protected from injury by the cap.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is an elevation of the improved cup.

Figure 2 is a section on line 2—2 of Figure 1.

Figure 3 is a section on line 3—3 of Figure 1.

Figure 4 is a section on line 4—4 of Figure 1.

In these views, 1 indicates the body of the cup which is provided with the threaded portion 2 for engaging a threaded hole in the bearing and with the wrench engaging portion 4. The upper or outer end of the cup is also provided with the wings 5 which are diametrically opposite each other. The cap is shown at 6, and said cap is provided with the oppositely arranged offset portions

7 at the sides thereof which form internal grooves 8 for receiving the wings. The cap is also provided with the oppositely arranged openings 9 with which the grooves 8 communicate so that after the cap is placed over the cup, with the wings engaging the grooves, and the cap pushed on to the cup, a quarter turn of the cap will cause

the wings to leave the grooves and enter the openings 9. The bottom wall of each opening is recessed, as at 10, to receive the lower portion of the wing, each wing having each lower corner beveled to engage corresponding bevels of the recesses, as clearly shown in Figure 1.

A coiled spring 11 is placed on the cap, with one end resting against the part 4 and its other end adapted to engage the shoulder 12 formed by the socket 13 in the cap so that this spring tends to push the cap upwardly or outwardly and thus holds the wings in the recesses 10. The cap carries the plunger 14 which is normally pressed downwardly by the coiled spring 15, the stem of the plunger being slidably carried by the cap, as shown.

From the foregoing, it will be seen that the spring 11 remains on the body of the cup and will be compressed when the cap is placed in position on the cup so that the spring will hold the locking means in operative position. The major portion of the spring occupies the socket 13 in the cap which will protect the spring from damage from a wrench engaging the part 4 and from blows and the like. By removing the cap, the plunger will be withdrawn from the cup so that lubricant can be placed therein. Then when the cap is put in place, the spring action of the plunger will automatically feed the lubricant into the bearing. The spring 11, being outside of the cup, will not come in contact with the lubricant and it will remain in place at all times.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A grease cup providing a body, a wrench engaging portion and a threaded portion formed with said body, locking wings formed with and extending from the body, a removable cap for the body and having internally arranged grooves, said cap being provided with laterally disposed openings

extending through the same and communicating with the grooves, the bottom of the openings having recesses for accommodating portions of the wings which have their lower corners beveled to be accommodated in corresponding beveled portions of the recesses, a coil spring encircling the body and engaging a portion thereof and the cap respectively for holding the wings in the recesses, and a spring plunger carried by the cap and mounted for movement in the body.

In testimony whereof I affix my signature.

MICHAEL HENRY.
